RAT GUARD

Stuart R. Thornton, 3700 26th St., San Francisco, Calif.
Filed Oct. 16, 1964, Ser. No. 404,261
4 Claims. (Cl. 114—221)

This invention relates to a rat guard for application to a hawser to prevent rodents, such as rats, from moving along the hawser from a pier or dock into a ship.

More particularly, it is an aim of the present invention to provide a rat guard of extremely simple construction which may be quickly applied to or removed from a hawser.

A further object of the invention is to provide a rat guard which will remain properly in place on a hawser at all times with its plane substantially perpendicular to the hawser, and which will not be affected by wind or tide so as to cause the guard to assume a canted position relative to the hawser so that a rat might successfully pass the guard and reach the ship along the hawser.

Various other objects and advantages of the invention will hereinafter become more fully apparent from the following description of the drawing illustrating a presently preferred embodiment thereof, and wherein:

FIGURE 1 is an elevational view of the rat guard, shown in an applied position;

FIGURE 2 is an enlarged sectional view taken substantially along the line 2—2 of FIGURE 1;

FIGURE 3 is a sectional view taken substantially along the line 3—3 of FIGURE 2;

FIGURE 4 is a sectional view taken substantially along the line 4—4 of FIGURE 2, and

FIGURE 5 is a fragmentary sectional view taken substantially along the line 5—5 of FIGURE 2.

Referring more specifically to the drawing, the rat guard in its entirety and comprising the invention is designated generally 7 and is shown in FIGURE 1 applied to a hawser 8 leading from a part of a ship 9 to a pile 10 of a pier or dock 11.

The rat guard 7 is composed primarily of a disc 12 formed of a resilient metal having a central opening 13, and a slit 14 which extends radially from part of the opening 13 through a part of the periphery of the disc 12. A portion 15 of the disc 12, which is disposed on one side of the slit 14, has an extension or flap 16 which overlies the slit 14 and a portion 17 of the disc 12, which is located on the other side of said slit.

A rod 18 is fixed to and projects from a side or face 19 of the disc 12, adjacent the central opening 13 and spaced from the inner end of the slit 14. The other end of the rod 18 terminates in an eye 20. The disc 12 is provided with an opening 21 which is located adjacent a portion of the periphery thereof and remote from the slit 14 and rod 18.

The opening 13 is of a size sufficient to accommodate a hawser of maximum size. To apply the rat guard 7 to the hawser 8 the rod 18 is positioned substantially perpendicular to the hawser 8 so that the plane of the disc 12 will be disposed substantially parallel to the hawser. The flap or extension 16 is then sprung away from the disc portion 17 so that said parts can be inserted over the hawser and so a part of the hawser will extend through the slit 14 which has been spread by the disc portion 15 being sprung away from the disc portion 17. The hawser

2

is then forced inwardly through the slit 14 between the portion 17 and the portions 15 and 16 until the hawser enters the opening 13, at which time portions 15 and 16 will spring back toward the plane of the portion 17 and the remainder of the disc 12. The disc 12 is then positioned perpendicular to the axis of the hawser 8 with the side 19 thereof facing toward the ship 9, so that the rod 18 will extend from the disc 12 toward the ship 9 and will be disposed substantially parallel to the hawser 8, as seen in FIGURES 1, 2 and 3.

The rat guard is moved a desired distance along the hawser 8 so that the disc 12 will be disposed between the pier 11 and the ship 9. One end of a lanyard 22 is secured to the eye 20 and the other end, not shown, is made fast to a part of the ship so that the lanyard will be taut. Thus, the lanyard 22 will cooperate with the rod 18 to maintain the disc 12 substantially perpendicular to the hawser 8, in addition to preventing the guard 7 from sliding down the hawser toward the dock 11. Thus, the disc 12 will be prevented from becoming canted relative to the hawser 8, which might permit a rat or other rodent to get past the rat guard in moving along the hawser toward the ship. A second lanyard 23 may be attached at one end to the disc 12 through its opening 21, with the other end, not shown, made fast to the ship 9, to further assist in holding the rat guard 7 in its position in FIGURE 1.

It will also be apparent that the parts 15 and 16 may be sprung away from the part 17 for readily disengaging the rat guard 7 from the hawser 8 by passing the hawser through the slit 14 from the opening 13 to the periphery of the disc 12.

Various modifications and changes are contemplated and may obviously be resorted to without departing from the function or scope of the invention, as hereinafter defined by the appended claims.

I claim as my invention:

1. A rat guard comprising a substantially circular disc of spring metal having a substantially central opening adapted to receive a hawser and a slit extending substantially radially from a part of said opening through a part of the periphery of the disc, a portion of the disc disposed along one side of the slit having an extension forming a flap overlying said slit and a portion of the disc disposed along the other side of the slit from said opening to the periphery of the disc, and said first mentioned portion and flap being sprung away from said last mentioned portion for spreading the slit to enable the hawser to be positioned in engagement with said opening or out of engagement with the disc.

2. A rat guard as in claim 1, and a rod fixed to and projecting from one side of the disc, adjacent said opening, and disposed substantially perpendicular to the plane of the disc, said rod being adapted to extend from the disc substantially parallel to the hawser toward a ship from which the hawser extends and having an eye at an end thereof disposed remote from the disc to which an end of a taut lanyard leading from the ship is adapted to be fastened for holding the rat guard from sliding movement on the hawser away from the ship and to prevent said disc from assuming a canted position relative to the hawser.

3. A rat guard as in claim 1, and a rigid lanyard anchoring member fixed to and projecting from a side of the disc adjacent said opening and to which a taut lanyard is adapted to be attached for holding the rat guard

against sliding movement on the hawser away from said lanyard and to prevent tilting movement of the rat guard relative to the hawser.

4. A rat guard comprising a substantially circular disc of spring metal having a central opening adapted to receive a hawser, said disc including overlapping portions extending from the opening to a portion of the periphery of the disc and defining a slit extending between the opening and said peripheral portion through which the hawser is moved into engagement with the opening or out of engagement with the disc when said overlapping portions 10 are sprung apart, and said overlapping portions be-

ing normally spring biased toward one another to close said slit.
